UNITED STATES PATENT OFFICE.

MARCUS C. HOPKINS, OF BROOKLYN, NEW YORK, ASSIGNOR, BY DIRECT AND MESNE ASSIGNMENTS, TO HOPKINS CORPORATION, A CORPORATION OF DELAWARE.

LOUD SPEAKER.

Application filed June 11, 1925. Serial No. 36,563.

This invention relates to electrical reproducing instruments, and more especially to loud speakers of the conical diaphragm type. A device embodying the invention can be 5 used advantageously with radio receiving sets, and also is suited to line wire reception, and to various other uses as will be understood by those skilled in the art.

I have discovered that fibrous diaphragms 10 of the conical type can be markedly improved in clarity of tone by placing the diaphragm under radial tension. The loud speaker described in detail in the accompanying specification explains one way in 15 which that discovery can be used to advantage.

It is an object of the present invention to provide a fibrous diaphragm of the conical type, which while stiff and resistant to distortion is nevertheless so supported that it 20 can move bodily under the action of an electrical translating movement having a short stroke. By making the cone of the right kind of fibrous material, and tensioning that 25 material as hereinafter described, and supporting the cone in such a way as to give it freedom of bodily movement, and by correlating with such a cone so supported an electrical movement having a powerful but 30 short stroke, I am able to produce results which in my opinion are far superior to those obtainable from loud speakers of the conical diaphragm type now regularly on the market.

35 It is a further object of the present invention to so mount the cone and its actuating movement that the loud speaker as a whole can be readily mounted in a box or cabinet, such, for instance, as the cabinet of 40 a phonograph, or the like.

Other objects and advantages will become clear from the following detailed description which is to be taken in conjunction with the accompanying drawings wherein.

45 Fig. 1 is a rear elevational view of a loud speaking instrument in accordance with this invention.

Fig. 2 is a cross-sectional view taken approximately along the vertical center line of 50 Fig. 1.

Fig. 3 is a fragmentary elevational view, partly in cross-section, showing details of construction of the electromagnetic actuating mechanism,

Fig. 4 is a cross-sectional view taken along 55 the line 4—4 of Fig. 3,

Fig. 5 is a fragmentary elevational view of the peripheral portion of a conical diaphragm, illustrating one way in which the periphery of the diaphragm is slotted and 60 partly cut away so as to form a considerable number of relatively small sectors which may be easily bent into the desired plane,

Fig. 6 is a cross-sectional view of the peripheral portion of the diaphragm shown in 65 Fig. 5,

Figs. 7 and 8 are elevational and cross-sectional views respectively showing the peripheral portion of the diaphragm illustrated in Figs. 5 and 6, but bent into a plane 70 which is normal to the axis of the diaphragm,

Figs. 9 and 10 are elevational and cross-sectional views of the peripheral portion of the diaphragm slotted radially but in which 75 the sectors thereby formed have not been cut away as in the case of the diaphragm of Figs. 5 to 8, inclusive, and

Figs. 11 and 12 are elevational and cross-sectional views similar to Figs. 9 and 10, but 80 showing the sectors bent into a plane normal to the axis of the diaphragm.

Inasmuch as the loud speaker of the present invention is especially suited for incorporation in the structure of an ornamental 85 cabinet, I have here shown it equipped with a cabinet of portable character. It will be clear that a much larger and more elaborate cabinet could be provided, as, for instance, when the loud speaker is built in as a permanent adjunct to an elaborate radio receiving set.

In Figs. 1 and 2, the rectangular wooden framework 1, together with the covers 2 and 3 form a casing structure for the loud 95 speaking instrument which comprises a conical diaphragm 4, an electromagnetic actuating mechanism 5, and a cast metal spider 6, to which the diaphragm 4 is attached and on which the electromagnetic actuating mechanism 5 is mounted. The conical diaphragm 4 is preferably of large diameter—generally more than nine inches—and is preferably made of very light, but rigid, paper so that it may be caused to vibrate bodily with little or no distortion. In order that the diaphragm may not be restrained against vibratory movement any more than is neces-

sary, the peripheral portion is slotted radially as illustrated in Figs. 9, 10, 11 and 12 wherein the radial slits are represented by reference numeral 4^a. In Fig. 9 the slits 4^a are shown closed as a result of the fact that the sectors formed by these slits are lying in the plane of the cone as indicated by Fig. 10.

In Fig. 11 the slits 4^a are shown open—
10 the openings being the result of the sectors being bent into a plane normal to the axis of the cone as indicated by Fig. 12. The edges of the peripheral sectors are secured to the peripheral rim of spider 6. This may be accomplished by cementing. As indicated at 4^c in Figs. 1 and 2 there is a considerable margin between the inner edge of the spider rim to which the cone is attached and the inner radius of the peripheral sectors.
15 The marginal portion 4^c bends quite readily thereby permitting free bodily vibratory movement of the cone. In order to further weaken the resistance to vibration, the peripheral sectors of the diaphragm may be
20 cut away as indicated at 4^b in Figs. 5 and 7. The triangular openings formed by cutting away the sectors may be as large as desired providing sufficient material is left to properly support the diaphragm.
25 Not all grades of paper are suited for use as a diaphragm material. The paper should be stiff. It should be porous and light in weight. A long fibered paper of porous structure and free from "loading" will serve
30 well, and any sizing should be of the fibers before felting and not of the sheet after it has been formed up. A layer of varnish or other like material applied to a finished cone is likely to impair greatly its sound producing qualities. Brittleness in the cone is a
35 desirable characteristic, provided the paper has at the same time sufficient toughness to withstand commercial transportation and ordinary handling during use.
40 It has been my experience that paper several years old is better than new stock, presumably because of an increased stiffening of the fibers due to aging. In any event the paper, or other fibrous material, used for
45 the cone must be capable of being bent without breaking in order that there may be formed in it the peripheral rim by which it is attached to the spider, and in order that it may have the requisite flexibility at the
50 base of the cone to permit of relatively free bodily movement desired by me.
55 In making the diaphragm illustrated a flat sheet of paper is first cut or punched to form a sector of the required radius and angle. Its periphery may be slotted and notched at the same time. The flat sector is then rolled up into a cone either by hand or through the aid of suitable mechanical devices, and is then glued along its radial joint.
60 The peripheral tongues are then bent as in-

dicated by Figs. 8 and 12 so that they will all lie in substantially the same plane and form a flat rim for the cone.

The next operation consists in gluing this rim to the flat face of the spider. I prefer to wet the spider with glue or cement and set the cone down on it, and then after the adhesive has commenced to set I grip the edge of the spider between my thumb and forefinger and press downwardly and outwardly on each paper tongue to slide it outward far enough to place a very sensible radial tension on the cone. All of the tongues are thus slipped outward over the half set adhesive. Mechanical devices may be used for effecting this radial tensioning of the cone if desired.

In addition to this radial tensioning the cone is tensioned on all circles concentric with its axis by the mere act of rolling the paper into a cone preparatory to gluing its radial joints. Consequently, after the tongues have been pulled outward, and the glue has set, the cone will be under tension both radially and circumferentially. This I have found greatly improves its tone producing qualities. Radial tensioning of the cone gives a slight inward bend to each radius of the cone, and though this is not enough to be readily detected by the eye, it can easily be detected by the ear of a user.

As an alternative procedure for putting the cone under radial tension, it is possible to dampen the cone before gluing it to the spider, and then let it shrink as its moisture content comes down to normal. Such an operation, however, must be carefully conducted for otherwise the cone will buckle and will be stressed in an irregular and troublesome manner, sometimes even to the extent of bulges or depressions in the surface. The use of a humidior and plenty of time for moistening and drying will help.

Also I have successfully tensioned cones by wetting the formed and glued cone with a formaldehyde solution, or an astringent, to shrink the paper somewhat. By virtue of the inherent lightness and stiffness of the paper and its circumferential and radial tensioning and the flexibility of the bend at which the cone is joined to the tabs constituting the rim, the diaphragm is able to vibrate substantially as a whole and with little or no bending or distortion of the cone proper. The stiffness of the cone permits the use of an electrical movement having a short stroke, and the freedom from restraint makes the cone so sensitive that the expenditure of but a small amount of power is needed to give satisfactory audibility.

The spider 6 is secured at its rim by means of four wood screws 7, to a wooden partition 8, which is secured to the inside of frame 1. The spider 6 is formed with an open rectangular center portion to which

the electro magnetic actuating mechanism is attached. By reason of the skeletonized formation of the spider the actuating mechanism is readily accessible.

- 5 The electrical movement disclosed herein cooperates well with a cone so constructed and mounted, for when its armature or reed is connected to the apex of the cone through a rigid bar attached to the armature near 70 its middle, there is delivered to the cone an impulse of short range and considerable power, and it is to such impulses that a tensioned and freely supported cone most readily responds. Novel features of the 75 10 electrical movement are claimed in my co-pending applications Serial No. 35,425 filed June 6, 1925 and Serial No. 36,562, filed June 11, 1925.

The electrical movements or electro magnetic actuating mechanism comprises a U-shaped permanent magnet 9, to each extremity of which is secured an angle iron 10, 11. To the angle iron 10 is attached a bifurcated soft iron pole shoe 12, between 80 15 the arms of which is inserted a specially formed member 13 of molded insulating material such as hard rubber or bakelite. The member 13 is provided with openings into each of which is inserted an electro-magnet coil 14, 15. In the arms of the soft iron shoe 12 there are secured threaded studs 16, 17 which function as adjustable pole pieces. The unthreaded portions of 85 90 these studs extend through the centers of the coils 14, 15, respectively, and are slotted to reduce eddy currents. A rigid soft iron or steel armature 18 is rigidly attached at one end to the angle iron 11—being preferably riveted thereto as shown—and its free 95 100 end portion is disposed substantially midway between the opposing ends of the pole pieces 16, 17. At a point along the midway portion of armature 18 there is secured a rod or connecting link 19, one end of which is attached to the cone 4. The connection between the link 19 and cone 4 is made through the medium of a hollow bolt 20, through which the link 19 passes and in which the link may be secured by a transverse set screw. In order to prevent damage 105 110 to the paper cone, its central portion is secured between two metal conical washers 21, 22 which are clamped together by means of the bolt 20 and nut 23.

55 The actuating mechanism forms a self contained unit and is attached to the spider by means of machine screws 24, 25.

Normally, that is to say, when no current is flowing in coils 14, 15, both adjustable pole pieces 16, 17 are of the same magnetic polarity and of equal strength. The armature 18 being disposed mid-way between these pole pieces it is attracted by both of them equally. The air gaps between pole 120 125 pieces 16, 17 and the armature 18 are adjust-

able and may readily be so adjusted that the best results are obtained under any predetermined conditions. The best results should be obtained when the normal magnetic attraction between one pole piece and the armature is equal and opposite to the magnetic attraction between the other pole piece and the armature.

If the instrument is operated through a transformer and has no normal direct current flowing through its coils it will generally be found that the two air gaps may be equal or substantially so. But if there is a normal direct current flowing through its coils, as is the case when it is connected directly in the output circuit of a vacuum tube amplifier, it may be found necessary to adjust one or both of the air gaps so that they are not equal when no current flows.

When the current flowing through coils 14, 15 fluctuates, the equilibrium of magnetic forces acting on the armature becomes upset and the armature is accordingly attracted toward one or the other pole pieces, depending upon the character of the current fluctuation. The amplitude of movement of the armature is proportion to the amplitude of the current fluctuation. Accordingly, if the current fluctuations correspond with sound waves, the armature will vibrate with the same frequency and with an amplitude proportionate to the amplitude of the sound waves which caused the current fluctuations.

The vibrations of the armature are short and powerful. The armature being of steel and relatively stiff and thick has a natural period above audibility. The natural elasticity of armature 18 is sufficient to permit the flexing of it, but the armature is so stiff and so supported at one end that it cannot strike the adjustable pole toward which it moves. The exact point at which rod 19 can best be attached to armature 18 lies about midway of the length of the armature and depends somewhat on the thickness and stiffness of the armature, and on the weight and other characteristics of the diaphragm to which rod 19 is rigidly attached. The exact point can best be found by trial.

Whatever kind of cone is used with the electrical movement here disclosed, best results, according to my experience, can be had by giving to the cone as a whole a freedom of bodily movement and a freedom from local bending and distortion. Radial tensioning will help. By thus co-ordinating the diaphragm to the electrical movement a highly satisfactory loud speaker can be obtained. Its tonal characteristics can be varied somewhat by changing the weight or stiffness of the vibratory armature or reed, or by changing the weight, size or thickness of the fibrous cone.

In the drawings, the covers each consist of 130 a narrow frame to which is attached what

may be conveniently termed an open work grill 31, consisting of woven cane. Any sort of perforated cover may be utilized, but the woven cane presents an attractive appearance, is durable, and adds but little to the weight of the instrument.

Electrical connections are made to the instrument through the medium of a conductor cord 26, terminal block 27, conductors 28, 10 29 and a pair of binding posts 30, which may be secured to the members 13.

A hinged lifting ring 32 provides a convenient means for lifting and carrying the instrument and when not in use is practically 15 out of sight.

The whole structure it will be seen is characterized by simplicity which is a virtue of very considerable importance. All parts of the instrument are easily accessible and are 20 of such form that they may be manufactured with but a very small outlay for special tools. The simplicity of the actuating mechanism is particularly outstanding. This it is observed, comprises a very small number of 25 parts all of which may be easily manufactured and quickly assembled without the need for any unusual skill.

The instrument is designed with a view to its being used as shown or, alternatively, 30 built into a cabinet such, for example, as a talking machine cabinet. Its form lends itself particularly well for the latter purpose.

I claim.

1. In a translating device, a conical fibrous 35 sound producing diaphragm tensioned radially, and a support, said diaphragm having a rim secured to said support for a part only of its width and flexibly connecting the diaphragm to the support to give the cone relative freedom for axial movement.

2. In a translating device, a conical fibrous sound producing diaphragm tensioned radially, and a support, said diaphragm having a flat rim secured to said support for a part 45 only of its width and flexibly connecting the diaphragm to the support to give the cone relative freedom for axial movement.

3. In a translating device, a conical fibrous sound producing diaphragm tensioned radially, and having a flat supporting rim consisting of a plurality of tabs integral with the cone.

4. In a translating device, a conical fibrous sound producing diaphragm tensioned radially and having a flat supporting rim consisting of a plurality of under-cut tabs, substantially as described.

5. In a translating device, the combination of a conical sound producing diaphragm tensioned radially and having a flat supporting rim consisting of a plurality of tabs, and a support for said diaphragm contacting with a part only of each tab.

6. In a translating device, the combination 65 of a conical fibrous sound producing dia-

phragm having a slotted rim, the portions of the rim between the slots being bent at an angle with respect to the walls of the cone, and a support for said diaphragm contacting with a part only of said rim.

7. In a translating device, the combination of a conical diaphragm having a plurality of integral under-cut tabs, bent at an angle with respect to the walls of the cone, and a support for said diaphragm contacting with a part only of each tab.

8. In a translating device, the combination of a diaphragm tensioned radially and having a plurality of integral tabs each of which is under-cut at its base to give the cone greater freedom of axial movement, and a support for said diaphragm contacting with a part only of each tab.

9. In a translating device, the combination of a fibrous sound producing diaphragm having a slotted rim, a support for said diaphragm contacting with a part only of said rim to give the cone relative freedom for axial movement, and an actuating device operatively connected with the apex of the cone to act thereon with a short and relatively powerful stroke, substantially as described.

10. In a translating device, the combination of a conical fibrous sound producing diaphragm tensioned radially and having a flat supporting rim consisting of a plurality of tabs integral with the cone, a support for said diaphragm contacting with a part only of said rim and allowing relative freedom of axial movement to said cone, and an actuating device operatively connected to the apex of said cone and operable thereon with a short and relatively powerful stroke, substantially as described.

11. In a loud speaker, a large conical diaphragm made of light weight stiff paper, the peripheral portion of said diaphragm being divided by radial slits to form a considerable number of peripheral sectors, said sectors being bent into a plane substantially normal to the axis of said diaphragm, a supporting member for said diaphragm, said sectors being secured to said member, said diaphragm being rendered substantially free to vibrate bodily by reason of the division of its peripheral portion, and actuating mechanism for said diaphragm.

12. In a loud speaker, a large conical diaphragm, a supporting member comprising a circular rim, the peripheral portion of said diaphragm being radially slitted to form a plurality of peripheral sectors, said sectors being bent into a plane substantially normal to the axis of said diaphragm, said sectors being attached at their outer edge portions to said rim, certain of said sectors being reduced in cross sectional area between the points at which they join the main body of said diaphragm and the points of attachment.

to said rim, the resistance to bodily vibration of said diaphragm being substantially reduced by reason of the reduction of cross sectional area of said sectors, and actuating mechanism for said diaphragm.

13. In combination, a rectangular casing having two perforated sides, and a loud speaker mounted within said casing, said instrument comprising a large conical diaphragm made of light weight stiff paper, means for resiliently supporting said diaphragms by its periphery so that it is substantially free to vibrate bodily, said supporting means including a spider having a substantially circular rim and a rectangular center portion, an actuating mechanism mounted on said rectangular center portion, and a connecting link between said actuating mechanism and said diaphragm.

14. In a loud speaker, a receptacle comprising a frame, said frame being provided with a partition having a circular opening, a spider mounted in said frame and supported by said partition, a diaphragm carried by said spider, actuating means mounted on said spider and connected to said diaphragm, and an open-work cover secured to at least one side of said frame.

15. In a translating device, the combination of a conical fibrous diaphragm, a support, and actuating means operatively connected with the apex of the conical diaphragm, said diaphragm being tensioned radially independent of said actuating means and being held in its state of tension by said support.

In testimony whereof I affix my signature
MARCUS C. HOPKINS.
